STEAM IRON WITH A FILLING VALVE ARRANGEMENT

Howard H. Schott, St. Paul, and Earl R. Burmeister, Minneapolis, Minn., assignors to General Mills, Inc., a corporation of Delaware

Application May 17, 1954, Serial No. 430,141

16 Claims. (Cl. 38—77)

This invention relates generally to steam irons of the domestic variety and pertains more especially to a particular valve arrangement therefor.

One object of the invention is to provide a steam iron which can be readily filled yet which will not inadvertently lose its liquid contents by reason of excessive tilting of the iron or through surging of the confined liquid during a pressing operation. More specifically, the invention contemplates the use of a special valve arrangement which will close off an avenue of escape through the filling opening, such action taking place automatically when the need arises without attention or effort on the part of the user. In this connection, it is contemplated that the iron may be side rested without loss of liquid, such special tilting of the iron being entirely within the province of the invention. Also the valve arrangement permits the nose of the iron to be tilted downwardly without such loss occurring as frequently would otherwise happen in performing certain motions preliminary to ironing.

In accordance with the foregoing object, an aim of the invention also resides in the provision of structure by which the valve mechanism may be intentionally rendered ineffectual, such structure being instrumental in retaining the valve open so that facile emptying of the contents may be accomplished whenever desired.

A further object of the invention is to achieve the above desiderata without detracting from the outer general appearance of the iron and also without noticeably increasing the over-all weight of the iron. Still further, the aims of the invention are realized in an inexpensive manner thus presenting a steam iron that may be manufactured at relatively low cost.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Figure 1 is a side view, largely in section, showing a basic embodiment which the invention may assume;

Figure 2 is a sectional view taken in the direction of line 2—2 of Figure 1.

Figure 3 is a fragmentary sectional view showing the nose of the steam iron tilted downwardly with a concomitant closing of the flap valve associated with the filling means.

Figure 4 is a rear view of the iron in a side rested position, a portion of the casing being removed to picture more clearly the operation of the flap valve when the iron is so positioned.

Figure 5 is a fragmentary side view with certain outer portions removed to show a modified version of the invention.

Figure 6 is an enlarged sectional view taken in the direction of line 6—6 of Figure 5.

2

Figure 7 is a view corresponding to Figure 3 but showing the modification pictured in Figure 5 with the parts thereof positioned so as to permit emptying of the steam iron.

5 Figure 8 is a still further embodiment which the invention may take, this view corresponding to that of Figure 5, and

Figure 9 is a view similar to Figure 8 but with the parts in a different position.

10 Referring now to the drawings, particularly Figures 1—4 thereof, it will be observed that the steam iron selected for the purpose of exemplifying the invention comprises a soleplate 10 having embedded therein a sheathed heating element 12. The heating element 12 is in circuit with a thermostat 14 which is adjusted by means of an upwardly extending shaft 16 carrying at its upper end a manipulating knob 18. The soleplate 10 is also provided with a cup-shaped zone 20 which serves as the means for generating steam from the water directed thereto. The steam thus generated is caused to course through a plurality of downwardly extending passages 22 leading to the pressing face of the iron.

25 Surmounting the soleplate 10 is a reservoir 24 which includes a bottom 26 and an upper shell portion 28 forming the top 30 and the sides 32 of the reservoir. In order to confine the steam that has been generated in the zone 20 to the forward portion of the iron a downwardly depending baffle 34 may be employed. As shown, this baffle 34 abuts the upper side of a gasket 36 and in this 30 way two compartments 38 and 40 are formed, the latter compartment containing the thermostat 14.

Secured in any suitable manner to the reservoir 24 is a handle 42. The upper portion of the handle is recessed at 44 and press fitted into the recess is an internally threaded sleeve 46.

35 Extending downwardly through the handle is a valve stem 48 having an upper threaded portion 50 received in the sleeve 46. At the top of the valve stem is a manipulated knob 52 by which the valve stem may be rotated. An intermediate portion of the 40 valve stem passes through the top 30 of the reservoir 24, there being provided a gasket or grommet 54 to effect the requisite sealing action. The lower end of the valve stem is configured so as to form a valve head 56. The valve head 56 cooperates with a valve seat 58 located in the bottom 26 of the reservoir. The seat 58 is centrally apertured at 60 so that when the valve stem is rotated in a direction to raise the valve head, then liquid contained in the reservoir 24 will flow gravitationally downwardly into the cup-shaped steam generating zone 20 where the water will be converted into steam which then 50 passes through the passages 22 via the compartment 38.

Up to this point the described structure is more or less of a conventional nature and has been selected only to set the environmental background for the subject matter now to be referred to, which subject matter collectively 55 is believed to be entirely novel. Accordingly, it will be noted that a vertically disposed filling tube 62 extends upwardly from the interior of the reservoir through the handle 42. At the lower end of the filling tube there is a compartment 64 formed by a bottom wall 66 and a rear wall 68, these walls being suitably connected to the inner surface of the shell portion 28 as by brazing. The rear wall 68 is composed of two sections, an upper vertical section 70 and a lower forwardly inclined section 72. The 60 upper section contains a relatively small aperture 74 which functions as a vent which will hereinafter be more fully referred to. The lower section, however, is provided with a relatively large aperture 76 through which the liquid introduced by way of the filling tube 62 must flow in reaching the major interior portion of the reservoir.

In order to preclude the escape of liquid from the res-

ervoir 24 through the filling tube 62 via the aperture 76 when the forward end of the iron is tilted sufficiently downwardly, or when the iron is moved to a side rest position or when the iron is moved back and forth during a pressing operation, which last movement will cause surging of the liquid contents in such a manner that they might splash out through the filling tube 62. A flap valve 78 is employed which will automatically cover the aperture 76 on the above described occasions. The flap valve is pivotally mounted to the upper section 70 of the rear wall by means of a pair of rearwardly directed ears 80 secured to said rear wall. The ears serve as bearings for a laterally extending pin 82 which has encircled thereabout portions 83 of the flap valve 78. Only the lower portion, that is that portion below the pin 82, is intended to cover the aperture 76. The upper portion of the flap valve is in the form of an upwardly directed tongue designated by the numeral 84. This tongue 84 performs an important role in preventing the flap valve from passing beyond a point displaced from the aperture 76 which could cause the flap valve to rotate through approximately 180° when the iron is moved onto either of its sides, thus preventing the flap valve from performing its function when the iron is so rested. With the tongue 84, however, as can probably be best understood from an inspection of Figure 4, the flap valve 78 is constrained so that it will bear against the inclined lower section when the iron is side rested just as it does when the nose of the iron is tilted downwardly as pictured in Figure 3.

Since it is contemplated that the iron will be moved into a side rest position, a pair of laterally extending projections 86 are attached to the shell 28 and these projections serve in conjunction with the handle 42 to maintain the soleplate 10 in a raised position from the surface upon which the iron is side rested.

From the foregoing description it is felt that the operation of our steam iron will be perfectly apparent. When the reservoir 24 is in need of liquid, such liquid is poured through the filling tube 62 and the liquid flows by gravity from the compartment 64 through the aperture 76 into the main portion of the reservoir. The aperture or vent 74 permits the reservoir to be filled almost completely since the air that would be otherwise entrapped in the upper region of the reservoir is permitted to escape until the level of the liquid reaches the lower end of the filling tube 62. Once the reservoir has been filled, the iron is in condition for a pressing operation when the soleplate has been heated sufficiently to generate the necessary steam. As is customary during an ironing operation, the iron is moved rather rapidly in a back and forward direction with a consequent result that the liquid confined in the reservoir is splashed or sloshed about. However, the pendulum-like manner in which the flap valve 78 is supported results in the valve covering the aperture 76 whenever the liquid tends to escape outwardly through this aperture. By reason of this arrangement, no liquid is permitted to pass out through the filling tube 62. Should the iron be tilted with its nose downwardly as depicted in Figure 3, here again the liquid will not escape from the reservoir since the weight of the lower part of the flap valve together with the liquid in the reservoir will cause the valve to cover the aperture 76 and thus close any possible avenue of egress out through the filling tube. As already indicated, the flap valve is mounted so that when the iron is moved onto either of its sides as illustrated in Figure 4, the flap valve will come up against the lower section of the rear wall which contains the aperture 76, thus in this instance closing off any possible escape of liquid via the filling tube.

Since the invention has made use of a gravity-actuated flap valve 78 a problem exists owing to the fact that at times it is desirable, if not necessary, to remove completely the liquid confined in the reservoir 24. In Figures 5, 6, and 7 specific structure has been provided for assuring, when properly manipulated, that the flap valve

will be retained in an open position to permit the emptying of the reservoir. To this end it is envisaged that a closure member 88 be made slidable with respect to the upper end of a somewhat modified filling tube 90. The closure member 88 is rendered slidable by making the closure member arcuate when viewed in cross section as plainly shown in Figure 6, the closure member being equipped with inturned flanges 92 which are slidably received in a pair of grooves 94 disposed in opposite sides of the handle 42.

Attached in a fixed manner at its upper end, such as by a screw 96, is a leaf spring 98 having an L-shaped configuration. The L-shaped configuration results in the provision of a relatively long leg 100 and a relatively short leg 102 bent at substantially right angles thereto. The relatively long leg 100 is bowed intermediate its ends at 104. By so configuring the spring 98 an actuating element 106 fixed to the closure member 88, such as by a rivet 108, will be instrumental in riding against the bowed portion 104 thus urging the leaf spring in a direction which results in the free end of the relatively short leg engaging the flap valve 78 to retain the flap valve in a displaced relation with respect to the aperture 76.

Therefore, whenever the closure member 88 is slidably moved upwardly for either the reception or emptying of liquid, the actuating element 106 will urge the leaf spring 98 in such a direction that the relatively short leg 102 will abut the flap valve and hold the valve open so that any liquid contained in the reservoir can be poured out through the filling tube 90 via the aperture 76, as clearly evidenced from the position of the parts depicted in Figure 7. However, when the closure member 88 is in a closed position such as that shown in Figure 5, the flap valve 78 is perfectly free to close automatically to prevent any inadvertent escape of liquid. Thus it will be apparent that the arrangement described results in assurance that liquid will not escape from the reservoir when it is not intended to do so.

Passing now to a description of the embodiment illustrated in Figures 8 and 9, it will be observed that a still different type of filling tube is utilized, this particular filling tube being designated by the numeral 110. Instead of the slideable closure member 88 there is provided a pivotal closure member 112 made so by reason of a pivot pin 114. Connected to the pivotal closure member 112 by another pin 116 is a rod 118 which extends downwardly through the filling tube 110 passing out the other side thereof by way of an aperture 120. The aperture 120 is so disposed that the free end of the rod 118 is in registry with the aperture 76 so that when the pivotal closure member 112 is moved from the position illustrated in Figure 8 to that shown in Figure 9, the free end of the rod will abut against the flap valve 78 to assure its retention in a displaced relation with respect to the aperture 76. Stated otherwise, the rod 118 is connected to the pivotal closure member in an articulative manner so that the closure member provides a crank or lever action whenever it is moved from a closed position to an open position, which movement causes the valve to be kept open so that liquid within the reservoir 24 may be poured out through the filling tube 110.

As in the more basic embodiment picture in Figures 1-4, the flap valve in the two embodiments of Figures 5-9 still includes the upwardly extending tongue 84 and this tongue functions in the same manner as in the earliest described embodiment to prevent excessive rotation of the flap valve which otherwise might result in the flap moving so far as to not cover the aperture 76 when the iron is placed in a side rest position.

As many changes could be made in the above construction and many apparently widely different embodiments of the invention could be made without departing from the scope thereof, it is intended that all matter contained in the above description or shown in the accompanying

drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim as our invention:

1. A steam iron comprising a soleplate having steam discharging means leading to its pressing face and steam generating means in heat receiving relation with its other face, a reservoir surmounting the soleplate having communication through a lower portion thereof with said steam generating means, a filling tube extending through the upper side of said reservoir near the forward end of the iron providing an opening through which liquid may be introduced to the reservoir, a compartment within the confines of the reservoir disposed adjacent the lower end of said filling tube including a bottom and a rear wall, said rear wall having an upper vertical section and a lower forwardly inclining section, the latter section having an aperture providing communication between said compartment and the interior of said reservoir, and a flap valve hingedly connected intermediate its ends to the upper section of said rear wall adjacent the lower end thereof so that the lower portion thereof is constrained to cover said aperture (said lower portion being of greater dimensions than said aperture) when the forward end of the iron is tilted sufficiently downward and the upper end thereof is constrained to abut the vertical section of said rear wall to prevent excessive departure of the lower valve portion from said lower rear wall section while the iron is being maneuvered into a side rest position.

2. A steam iron in accordance with claim 1 in which there is a smaller aperture disposed in the upper section of said rear wall for venting the reservoir to permit filling thereof to a level above said first named aperture.

3. A steam iron comprising a soleplate having steam discharging means leading to its pressing face and a steam generating boiler in heat receiving relation with its other face, a reservoir surmounting the soleplate having communication through a lower portion thereof with said steam generating boiler and provided with filling opening means disposed in an upper portion thereof through which liquid may be introduced to the reservoir, said filling means including a pivotally mounted flap valve disposed within said reservoir and arranged to close automatically said opening, a manually operable closure member for said opening located externally of said reservoir; and means interengageable with said closure member and said flap valve for retaining said flap valve in an open position when said closure member is in an open position.

4. A steam iron comprising a soleplate having steam discharging means leading to its pressing face and steam generating means in heat receiving relation with its other face, a reservoir surmounting the soleplate having communication through a lower portion thereof with said steam generating means, filling means including a tube extending through the upper side of said reservoir near the forward end of the iron through which liquid may be introduced to the reservoir, said filling means having a lower opening through which the liquid may be discharged directly into the reservoir from said tube, means including a pivotally mounted flap valve arranged to engage said filling means adjacent said lower opening of the filling means when the forward end of the steam iron is tilted downwardly sufficiently from a horizontal position, thereby preventing undesired escape of liquid via said filling means, a closure member movable between two positions to either open or close the upper end of said tube, and means interengageable with said closure

member and said flap valve for retaining said flap valve in an open position when said closure member is moved to its open position to permit intentional removal of liquid from said reservoir.

5. A steam iron comprising a soleplate having steam discharging means leading to its pressing face and steam generating means in heat receiving relation with its other face, a reservoir surmounting the soleplate having communication through a lower portion thereof with said steam generating means, and a filling tube extending through the upper side of said reservoir near the forward end of the iron providing an opening through which liquid may be introduced to the reservoir, a slidable closure member for closing the upper end of said filling tube, a pivotally mounted flap valve arranged to move in a pendulum fashion near the lower end of the filling tube, seat means having an aperture therethrough which is covered by said flap valve when the forward end of the steam iron is tilted downwardly sufficiently from a horizontal position, thereby preventing undesired escape of liquid via said filling tube, and cam means operable by said closure member when moved to open position to engage said flap valve to retain said valve in an unseated position with respect to said seat means.

6. A steam iron in accordance with claim 5 in which said cam means includes a leaf spring fixedly anchored at its upper end with its lower end engageable with said flap valve, and an actuating element carried by said closure member for riding against a portion of said leaf spring to urge said spring against said flap valve to produce said retention of said valve in an unseated position with respect to said seat means when said closure member is moved to open position.

7. A steam iron comprising a soleplate having steam discharging means leading to its pressing face and steam generating means in heat receiving relation with its other face, a reservoir surmounting the soleplate having communication through a lower portion thereof with said steam generating means, a filling tube extending through the upper side of said reservoir near the forward end of the iron providing an opening through which liquid may be introduced to the reservoir, a slidable closure member for closing the upper end of said filling tube, a compartment within the confines of the reservoir disposed adjacent the lower end of said filling tube including a bottom and a rear wall, said rear wall having an upper vertical section and a lower forwardly inclining section, the latter section having an aperture providing communication between said compartment and the interior of said reservoir, and a flap valve hingedly connected intermediate its ends to the upper section of said rear wall so that the lower portion thereof is constrained to cover said aperture when the forward end of the iron is tilted sufficiently downward and the upper end thereof is constrained to abut the vertical section of said rear wall to prevent excessive departure of the lower valve portion from said lower rear wall section while the iron is being maneuvered into a side rest position, a substantially L-shaped spring including a relatively long leg having a bowed intermediate portion and a relatively short lower leg, the upper end of said relatively long leg being fixedly anchored adjacent the upper end of said filling tube and said relatively short leg being disposed for movement through said aperture in the rear wall, and an actuating element carried by said closure member for riding against the bowed portion of said spring to cam said spring in a direction to cause engagement of the relatively short leg thereof with said flap valve to retain said flap valve displaced from said rear wall aperture even when the forward end of the iron is tilted downward.

8. A steam iron in accordance with claim 7 in which the upper end of said flap valve is constrained to abut the vertical section of said rear wall to prevent excessive departure of the lower valve portion from said lower

rear wall section while the iron is being maneuvered into a side rest position.

9. A steam iron in accordance with claim 8 in which means is provided extending through said filling tube and engageable through said aperture with the flap valve for intentionally retaining said valve at times in a spaced relation with said aperture.

10. A steam iron comprising a soleplate having steam discharging means leading to its pressing face and steam generating means in heat receiving relation with its other face, a reservoir surmounting the soleplate having communication through a lower portion thereof with said steam generating means, a filling tube extending through the upper side of said reservoir near the forward end of the iron providing an opening through which liquid may be introduced to the reservoir, a pivotal closure member for closing the upper end of said filling tube, a pivotally mounted flap valve arranged to move in a pendulum fashion near the lower end of the filling tube, seat means having an aperture therethrough which is covered by said flap valve when the forward end of the steam iron is tilted downwardly sufficiently from a horizontal position, thereby preventing undesired escape of liquid via said filling tube, and an elongated member pivotally connected to said closure member and operable thereby when moved to open position to engage said flap valve to retain said valve in an unseated position with respect to said seat means.

11. A steam iron comprising a soleplate having steam discharging means leading to its pressing face and steam generating means in heat receiving relation with its other face, a reservoir surmounting the soleplate having communication through a lower portion thereof with said steam generating means, a filling tube extending through the upper side of said reservoir near the forward end of the iron providing an opening through which liquid may be introduced to the reservoir, a pivotal closure member for closing the upper end of said filling tube, a compartment within the confines of the reservoir disposed adjacent the lower end of said filling tube including a bottom and a rear wall, said rear wall having an upper vertical section and a lower forwardly inclining section, the latter section having an aperture providing communication between said compartment and the interior of said reservoir, and a flap valve hingedly connected intermediate its ends to the upper section of said rear wall so that the lower portion thereof is constrained to cover said aperture when the forward end of the iron is tilted sufficiently downward and the upper end thereof is constrained to abut the vertical section of said rear wall to prevent excessive departure of the lower valve portion from said lower rear wall section while the iron is being maneuvered into a side rest position, an elongated rod having its upper end pivotally connected to said closure member at a locus offset from the locus about which said closure member pivots, said filling tube having an aperture near its lower end through which said rod extends for supporting the lower end of the rod so that it will move through said rear wall aperture when the closure member is pivoted to open position to engage and displace the flap valve from said rear wall aperture even when the forward end of the iron is tilted downward.

12. A steam iron in accordance with claim 11 in which the upper end of said flap valve is constrained to abut the vertical section of said rear wall to prevent excessive departure of the lower valve portion from said lower rear wall section while the iron is being maneuvered into a side rest position.

13. A steam iron in accordance with claim 12 in which means is provided extending through said filling tube

and engageable through said aperture with the flap valve for intentionally retaining said valve at times in a spaced relation with said aperture.

14. A steam iron comprising a soleplate having steam discharging means leading to its pressing face and steam generating means in heat receiving relation with its other face, a reservoir surmounting the soleplate having communication through a lower portion thereof with said steam generating boiler and provided with filling opening means disposed in an upper portion thereof through which liquid may be introduced to the reservoir, said opening means including a pivotally mounted flap valve disposed within said reservoir and arranged to close automatically said opening means to prevent reverse flow of liquid via said filling opening means, and means for preventing movement of said flap valve past a predetermined open position so that said flap valve will always close when the steam iron is placed in a side rest position.

15. A steam iron comprising a soleplate having steam discharging means leading to its pressing face and steam generating means in heat receiving relation with its other face, a reservoir surmounting the soleplate having communication through a lower portion thereof with said steam generating boiler, filling means including a tube extending through the upper side of said reservoir near the forward end of the iron through which liquid may be introduced to the reservoir, said filling means having a lower opening through which the liquid may be discharged directly into the reservoir from said tube, means including a pivotally mounted flap valve arranged to engage said filling means adjacent said lower opening of the filling means when the forward end of the steam iron is tilted downwardly sufficiently from a horizontal position, thereby preventing undesired escape of liquid via said filling means, and a manipulating means extending from the interior of said reservoir to the exterior thereof for intentionally retaining said flap valve at all times in an open position.

16. A steam iron comprising a soleplate having steam discharging means leading to its pressing face and steam generating means in heat receiving relation with its other face, a reservoir surmounting the soleplate having communication through a lower portion thereof with said steam generating boiler and a filling tube extending through the upper side of said reservoir near the forward end of the iron through which liquid may be introduced to the reservoir, wall means adjacent the lower end of the filling tube forming a compartment, said wall means having an aperture through which the liquid must pass on its way to the interior of the reservoir, means including a pivotally mounted flap valve of sufficient dimensions arranged to engage said wall means and to cover said aperture automatically when the forward end of the steam iron is tilted downwardly sufficiently from a horizontal position, thereby preventing undesired escape of liquid via said aperture, compartment and filling tube, and means extending through said filling tube and engageable through said aperture with the flap valve for intentionally retaining said valve at all times in a spaced relation of said aperture.
